UNITED STATES PATENT OFFICE.

WILLIAM PERRY HALL, OF PIQUA, OHIO.

SMOKE-CONSUMING DEVICE.

SPECIFICATION forming part of Letters Patent No. 283,600, dated August 21, 1883.

Application filed December 4, 1882. (No model.)

To all whom it may concern:

Be it known that I, WILLIAM P. HALL, of Piqua, in the county of Miami, and in the State of Ohio, have invented certain new and useful Improvements in Devices for Consuming Smoke; and I do hereby declare that the following is a full, clear, and exact description thereof, reference being had to the accompanying drawings, and to the letters of reference marked thereon, making a part of this specification.

This invention relates to certain improvements in smoke-consuming furnaces; and it has for its objects to provide improved means for supplying heated air to the burning fuel, so as to insure the thorough combustion of the gases and carbon thereof, as more fully hereinafter specified.

The above-mentioned objects I attain by the means illustrated in the accompanying drawings, in which Figure 1 represents a longitudinal sectional view, showing my invention applied to a steam-boiler furnace, the section being taken on the line *x x* of Fig. 2; Fig. 2, a front elevation of the furnace; and Fig. 3 represents a transverse or cross-sectional view on the line *y y* of Fig. 1.

The letter A indicates the masonry or brick walls inclosing and supporting a steam-boiler, B, and within which, and below the boiler, is located and constructed my improved furnace C, which is formed or built of fire-brick, or any other material the nature of which adapts it to withstand the action of excessive heat.

The letter C' designates the fire-box of the furnace, the same being provided with suitable grate-bars, D, and an ash-pit, E, immediately below the said bars.

The letter F indicates a fire-bridge just back of the fire-box, and G another or second fire-bridge at the rear of the bridge F, said bridges being made integral with and forming a part of the improved furnace. Between said fire-bridges is a chamber, H, having a curved bottom, as indicated in Fig. 1 of the drawings, and directly above the curved bottom of said chamber is located an arched partition, I, which embraces the lower part of the boiler and extends downward about half-way

of the said chamber, forming, with the fire-bridges, deflectors, which cause the flames from the combustion-chamber or fire-box to take a tortuous course in their passage under the boiler.

The letter K indicates a lateral air-passage in the lower portion of the masonry of the furnace, from which branch the passages L, leading to the chamber H, in order to supply air to the unconsumed gases passing over from the burning fuel, in order to insure their consumption.

The letter R indicates a damper located in the eduction-flue of the boiler-furnace, and controlled by a rod, S, by means of which the draft through the furnace may be regulated.

The passages L terminate in a series of openings, *l*, arranged in two parallel rows, one above the other, and alternating with each other, as indicated in Fig. 3 of the drawings. This causes the heated air to be delivered in a thin sheet or sheets, or a series of parallel jets, to the gases passing from the fire-box, insuring thorough and effective combustion.

The chamber H at one side is provided with an opening, T, (provided with a suitable plug,) through which any ashes or accumulations may be removed from the said chamber.

Having thus described my invention, what I claim, and desire to secure by Letters Patent, is—

The combination, with a steam-boiler furnace and the fire-box C thereof, of the bridge F, having an inclined rear wall, the partition I, extending below the upper edge of the bridge F, the bridge G at the rear of partition I, and the passages L and *l*, leading into the chamber H at different points and levels, the said passages L communicating with a passage, K, leading to the open air, substantially as and for the purpose specified.

In testimony whereof I affix my signature, in presence of two witnesses, this 3d day of July, 1882.

WILLIAM PERRY HALL.
